JOHN T. PHIPPS, OF HUNTINGTON PARK, CALIFORNIA, ASSIGNOR OF ONE-FOURTH TO
MATTIE M. NEWCOMB

PACKER

Application filed December 28, 1927. Serial No. 243,039.

My invention relates to packers which are used in many arts but, for the purpose of disclosure, my invention will be described as embodied in an oil well packer.

5 In drilling oil wells and in producing oils from these wells, it often becomes quite advantageous to form a seal at some point down in the well between a string of well casing and a tubing inserted therein. Such 10 a seal is usually formed by a rubber packer carried by the tubing and expanded at the desired point by a suitable mechanism. It is usually desirable that these packers remain in place an indefinite length of time 15 during which the packer gradually adheres to the casing rather tenaciously. When it becomes necessary to remove the packer, this is accomplished by pulling the tubing upward so that a shoulder formed theron abuts 20 against the lower end of the packer so as to push it upward. The adhesion of the packer to the casing, however, causes this upward pressure to expand the packer so that it can be displaced only by lifting with sufficient 25 force to tear the packer to pieces. Because of this difficulty of dislodging the packers in general use, there has developed a prejudice against using them.

It is therefore an object of my invention 30 to provide a packer which may be easily dislodged from expanded position.

Another object of my invention is to provide a packer having a means for positively moving it between expanded and contracted 35 positions.

Further objects and advantages will be made manifest in the following description and in the accompanying drawing in which a preferred embodiment of my invention is 40 illustrated.

In the drawing:

Fig. 1 is a fragmentary vertical sectional view illustrating a packer embodying the features of my invention and showing the 45 packer in contracted position.

Fig. 2 is a view similar to Fig. 1, showing the packer in expanded position.

Figs. 3 to 7 inclusive are horizontal sectional views taken on the correspondingly 50 numbered lines of Fig. 1.

Fig. 8 is a side elevational view of a packing member of my invention, partially broken away to show the reinforcing member thereof.

Referring specifically to the drawing, the 55 numeral 10 indicates diagrammatically a section of well casing, and extending downward into the casing 10 is a tubing 11. The casing 10 and tubing 11 may be of any desired character and for any desired purpose 60 which may require that a seal be formed in an annular space 12 between the casing 10 and the tubing 11. In order to effect such a seal, a packer 16, which embodies the features of my invention, is connected to the 65 tubing 11 when this is extended downward into the casing 10. The packer 16 may be disposed at the lower end of the tubing 11, or it may be disposed at any point intermediate the lower and upper ends of the tubing. 70

The packer 16 includes a head 20 having a threaded bore 21 which is screwed upward onto the lower end of that portion of the tubing 11 which is disposed above the packer 16. Provided on the head 20, to extend outward from the upper portion thereof, is a series of projections 22 which are spaced apart to provide channels 23, clearly illustrated in Fig. 3, through which fluid may 80 pass around the head 20. Provided in a pair of diametrically opposite projections 22 are holes 24, for a purpose to be described later. Formed upon the lower portion of the head 20 is a tapering surface 26.

Threaded at its upper end and screwed upward into the lower part of the threaded bore 21 is a tubular inner sleeve 28 which has an inside diameter equal to that of the tubing 11. Formed on the sleeve 28, to extend outward therefrom a short distance downward from the upper end thereof, is an annular stop-shoulder 29. The lower end of the sleeve 28 is threaded so as to receive a threaded collar 30 by which it may be connected to other lengths of the tubing 11 which are disposed beneath the packer 16. Extending outward from the sleeve 28, near the lower end thereof, is a pair of diametrically opposed pins 33. 85 90 95

Disposed about the sleeve 28 is a tubular abutment member 35 having a bore 36 at its 100

lower end which slidably fits over a lower portion of the sleeve 28, and a counterbore 37 which slidably fits over the stop-shoulder 29. Formed on the lower end of the abutment member 35 is a tapered surface 40. Formed on the abutment member 35, so as to extend outward therefrom at its upper end, are projections 42, clearly illustrated in Fig. 4, forming open spaces 43 through which fluid is adapted to pass in flowing around the abutment member 35. The upper end of the abutment member 35 is internally threaded, and an externally threaded stop-ring 44 is screwed therein so as to abut against the stop-shoulder 29 and limit downward movement of the abutment member 35. Disposed in the counterbore 37 so that its opposite ends engage the stop-shoulder 29 and a shoulder 45, formed at the junction of the bore 36 and the counterbore 37, is an expansion spring 46 which tends to retain the abutment member 35 in its downmost position.

Slidably fitting over the lower portion of the sleeve 28, below the lower end of the abutment member 35, is a short slip-sleeve 48 having slots 49 formed in opposite portions of the wall thereof. Each slot 49 has a horizontal upper portion 50 and a vertical lower portion 51, and connecting these portions is an oblique slot portion 52.

Connected at their lower ends to the sleeve 48 as by rivets 55 is a series of resilient arms 56 which are preferably four in number. Mounted on the upper ends of the resilient arms 56 are slips 57 which have downwardly inclined teeth 58 formed on the outer surfaces thereof, and beveled surfaces 60 formed on the inner surfaces thereof. Secured at its lower end against each of the resilient arms 56 by the rivets 55 is one of a series of outwardly curving springs 62, the upper end of each of which slidably contacts the resilient arm 56 to which it is connected at its lower end. The curved form of the springs 62 causes the central portion of each of these to frictionally engage an inner surface 65 of the casing 10.

Disposed about the upper end of the inner sleeve 28 is an annular packing member 68 which is formed of a resilient material which is preferably rubber. Embedded in the packing member 68 is a plurality of relatively heavy reinforcing members 69 which are disposed spirally in the packing member or, in other words, obliquely relative to the vertical axis of the packing member 68. For purposes of making the description clear, this axis will be referred to as the axis of contraction of the packing member 68. In the present embodiment, the heavy reinforcing members 69 are two in number and the upper ends 70 thereof extend upward through the holes 24 and threadedly receive nuts 71 upon their upper ends, which nuts engage the upper face 65 of the head 20 when the packing member 68

is in the position in which it is shown in Fig. 1.

Also embedded in the packing member 68 are two series 72 and 73 of spirally arranged light stiff reinforcing members which are disposed in crossing relation so as to substantially form a wire screen, having a relatively large mesh, as clearly shown in Fig. 8. The series of reinforcing members 72 and 73 may either be loosely connected together where they cross each other as by knotted cord ties 74, or they may be held in their relative positions to each other merely by being embedded in the packing member 68 when this is vulcanized. It will readily be seen that to apply pressure against the opposite ends of the packing member 68 on its axis of contraction causes the diameter of the screen formed by the light reinforcing members 72 and 73 to increase so as to expand the packing member 68. It is also pointed out that when the heavy reinforcing members 69 are drawn upwardly so as to tend to straighten these to a more nearly parallel position relative to the axis of contraction of the packing member 68, this member is caused to contract by the contraction of the screen formed by the reinforcing members 69, 72, and 73.

The operation of the packer 16 is as follows:

When the packer 16 is lowered into the casing 10 upon the tubing 11, the sleeve 48 is positioned upon the inner sleeve 28 so that the pins 33 are disposed in the upper portions 50 of the slots 49. This retains the slips 57 in their downward or retracted position relative to the abutment member 35 so that the teeth 58 do not engage the inner surface 65 of the casing 10 and thus permit the packer 16 to be readily lowered through the casing 10 to the position where it is desired that a seal be formed by the packer. When the packer 16 has reached this position, the tubing 11 is rotated in a clockwise direction. This rotates the pins 33 and, owing to the friction between the springs 62 and the casing 10, the sleeve 48 is held stationary and the pins 33 pass from the upper portion 50 of the slot 49 through the diagonal portion 52 of this slot and into the lower portion 51 thereof. As the sleeve 28 thus moves downward relative to the sleeve 48, the tapered surface 40, formed at the lower end of the abutment member 35, spreads the slips 57 so that the teeth 58 engage the inner surfaces 65 of the casing 10 and prevent further downward movement of the abutment member 35. The sleeve 28 may still move downward, however, by compressing the spring 46 and as this is done, the packing member 68 contacts the abutment member 35 so that further downward movement of the sleeve 28 causes the tapered surface 26 of the head 20 to expand the packing member 68 into tight en-

gagement with the inner surface 65 of the casing 10, as shown in Fig. 2.

As the expansion of the packing member 68 is thus effected, the upper ends 70 of the reinforcing member 69 slide upward through holes 24, as clearly shown in Fig. 2. The expanded position of the packing member 68 is maintained by the weight of the tubing 11 which is allowed to rest downward upon the packer 16 until it becomes necessary to remove the packer. When a rubber packer is allowed to stay in position a certain length of time, it adheres to the inner surface of the casing in which it is set so that it becomes exceedingly difficult to remove the packer. This is especially true when the removal is attempted by upward pressure against the lower end of the packer, as the adhesion of the packer to the wall of the casing causes this upward pressure merely to expand the packer instead of loosening it from the casing.

To release the packer 16, the tubing 11 is drawn upward until the nuts 71 are positioned as shown in Fig. 1; after which the contraction of the reinforcing members 69, 72, and 73 in the packing member 68 positively contract the packing member 68 away from the wall of the casing 10 into the position in which it is shown in Fig. 1. Thus the packer 68 is not damaged in any way and a minimum of upward pressure is required for effecting its removal from sealing position.

It is of course to be understood that the packing member of my invention may be used as a swab rubber or in any place where a positively expanding and contracting packing member might be used to advantage.

I claim as my invention:

1. In a packer, the combination of: an annular resilient packing member adapted to be disposed in the space between a casing and a tubing inserted therein; relatively stiff reinforcing members spirally embedded in said packing member; means for expanding said packing member to form a seal in said space; and means for contracting said packing member by drawing upon said reinforcing members.

2. In a packer, the combination of: an annular resilient packing member adapted to be disposed in the space between a casing and a tubing inserted therein; relatively stiff spiral reinforcing members disposed adjacent to and adapted to expand with and to exert a contracting force against said packing member; means for expanding said packing member to form a seal in said space; and means for contracting said packing member by drawing upon said reinforcing members.

3. In a packer, the combination of: a resilient packing member adapted to be disposed in a space enclosed by walls; relatively stiff reinforcing members disposed obliquely

relative to an axis of contraction of said packer and adapted to expand with, and exert a contracting force against said packer; and means for drawing upon said reinforcing members to cause a contraction of said packer.

4. In a packer, the combination of: a resilient packing member adapted to be disposed in a space enclosed by walls; relatively stiff reinforcing members disposed obliquely relative to an axis of contraction of and embedded in said packer; and means for drawing upon said reinforcing members to cause a contraction of said packing member.

5. In a packer, the combination of: a resilient packing member adapted to be disposed in a space enclosed by walls; relatively stiff reinforcing members spirally embedded in said packer; and means for drawing upon said reinforcing members to cause a contraction of said packing member.

6. In a packer, the combination of: a resilient packing member adapted to be disposed in a space enclosed by walls; reinforcing members disposed obliquely relative to an axis of contraction of said packer and adapted to expand with, and exert a contracting force against said packer; and means for drawing upon said reinforcing members to effect a contraction of said packer.

7. In a packer, the combination of: a resilient packing member adapted to be disposed in a space enclosed by walls; relatively stiff reinforcing members disposed obliquely relative to an axis of contraction of said packer and adapted to expand and contract with said packer; and means for moving said reinforcing members so that said members exert an expansive or contractive effort against said packing member.

8. A combination as in claim 1 in which certain of said reinforcing members are disposed in crossing relation with other of said reinforcing members.

9. A combination as in claim 2 in which certain of said reinforcing members are disposed in crossing relation with other of said reinforcing members.

10. A combination as in claim 3 in which certain of said reinforcing members are disposed in crossing relation with other of said reinforcing members.

11. A combination as in claim 4 in which certain of said reinforcing members are disposed in crossing relation with other of said reinforcing members.

12. A combination as in claim 5 in which certain of said reinforcing members are disposed in crossing relation with other of said reinforcing members.

13. A combination as in claim 6 in which certain of said reinforcing members are disposed in crossing relation with other of said reinforcing members.

14. A combination as in claim 7 in which

certain of said reinforcing members are disposed in crossing relation with other of said reinforcing members.

- 5 15. In a packer, the combination of: a body; a packing member mounted on said body; means for inserting said packer any desired distance into a confined space; a series of projections extending radially from said body for centralizing said packer in said 10 space as it is being inserted thereinto so that said packing member will not rub on a wall confining said space; and means on said body for expanding said packing member into sealing engagement with said walls when said 15 packer has reached a desired position in said space.

In testimony whereof, I have hereunto set my hand at Los Angeles, California, this 22nd day of December, 1927.

20 JOHN T. PHIPPS.
